WHEEL PULLER

Filed May 2, 1929

Inventor
George W. Grebenstein

Ellis Speaef.
By Attorney

UNITED STATES PATENT OFFICE

GEORGE W. GREBENSTEIN, OF NEWTONVILLE, MASSACHUSETTS

WHEEL PULLER

Application filed May 2, 1929. Serial No. 359,828.

Relative to draft apparatus and particularly to wheel pulling devices, I disclose my present invention as follows. As illustrated in wheel pulling devices the problem has been 5 to provide a simple device of practical efficiency and generally of some range of utility.

Such devices are of well known types which have come into popular acceptance and 10 are therefore most practically useful to the public which most easily adapts itself to improved devices of familiar type.

I therefore show and describe herein a puller in accordance with my invention based 15 on one of my prior devices, but involving improvements capable of other embodiment. In describing such an improved wheel puller I have provided drawings in which—

Fig. 1 is a partly sectioned elevation of 20 such a device, and

Fig. 2 is a bottom view of the same partly broken away.

Such a wheel puller as is thus indicated comprises a frame or carrier piece 1 having 25 a central bearing 2 apertured and threaded as at 3.

This constitutes the bearing for the take up screw 4 which has a wrench head 4¹ by which it can be turned into thrust relationship to the end of a shaft. On each side of this bearing are lateral guide slots 5 across the top of which are half cylindrical trunnion bearings 7.

In these rest the trunnion heads 8 from 35 which depend arms 9 which develop into bases 10 adapted to provide for clamping engagement with a wheel hub.

To enable clamping engagement of the arms 9 with wheel hubs of different sizes, I 40 provide flange engaging ledges 10¹ and 10² on the inner faces of said arms 9. Such engagement is made by a slip ring 11 which can be driven down on the tapered surface 10^a of the portion 10. The engagement is frictional.

The trunnions 8 are held in place by pins 12 across the slots 5 which guide the squared portions 9¹ of the arms 9. The screw 4 is 45 axially bored as at 14 for part of its length 50 and in this bore is a drive pin 15. This drive

pin 15 is exposed at the lower end of the screw 4 which is in practice brought up against the end of the axle shaft.

The screw 4 is slotted as at 16 to receive a tapered key 17 which has a driving engagement with the upper end of the pin 15. By such a device the ultimate reluctance of a "pull" can be overcome. The screw 4 is thus used first to get contact and stress. The drive pin 15 is then used for loosening by shock and the screw then used finally for the following off phase of removal.

The device illustrated and described is presented as illustrative but is in itself simple and efficient.

The jaws 10 while freely mounted and self-adjusting are nevertheless in permanent assembly as is also the closing ring 11. Their external conicity 10^a provides a free sliding surface for the ring 11 when engaged with a hub flange. Moreover while effective as conic sections (parallel to axis) when the jaws 10 are open they assume when closed positions or exterior surface which are cylindric in character. The ring 11 therefore wedges the jaws as it is pushed down but when seated against the flange 10^b has no return tendency.

The pin 15 provides for the loosening or starting impact without danger to the screw threads and the device can be put in place and operated by a single mechanic with ease and dispatch.

The loose mounting of the jaws 10 as by the trunnion 8 permits a slight movement of the jaws relative to the screw 4 so as to permit a self-centering of the puller on the axle.

My concepts are capable of various embodiments of variations. Invention is claimed within liberal limits of interpretation of claims such as I now present.

What I therefore claim and desire to secure by Letters Patent is:

1. A wheel puller or the like comprising a frame having a central threaded bearing and a pair of jaw supports on each side thereof, a pair of jaws supported in said bearings, a closing ring slidably retained about said jaws, a thrust screw threaded in said bearing, a drive pin axially of said screw and a driving

key disposed through said screw and having a driving contact with said pin.

2. A wheel puller or the like comprising a frame having a central threaded bearing and a pair of jaw supports on each side thereof said supports having trunnion bearings on their upper faces, a pair of jaws each having a trunnion at its upper end and supported in said bearings, said jaws having tapered outer faces and flange engaging inner faces, a closing ring slidably retained about said jaws, a thrust screw threaded in said bearing, a drive pin axially of said screw and a driving key disposed through said screw and having a driving contact with said pin.

3. A device for pulling a wheel or the like from an axle comprising a frame, means for detachably connecting said frame with the wheel or the like to be pulled, a screw threaded through said frame for engagement at its inner end with the end of the axle, said screw having a longitudinally extending bore opening through the axle engaging end thereof and also having a transverse slot intersecting said bore, a pin within said bore extending from said slot to the axle engaging end of the screw, and a wedge insertable through said slot against the adjacent end of said pin and adapted to be driven to force the screw and the frame longitudinally with respect to the pin.

4. A device for pulling a wheel or the like from an axle comprising a frame, means for detachably connecting said frame with the wheel or the like to be pulled, a member carried by said frame and movable with respect thereto against the end of the axle to impose a pulling stress on the wheel, a pin carried by said member and movable with respect thereto against the end of the axle, and means reacting from said pin through said member to move said frame in a direction to effect pulling of the wheel from the axle.

45. In testimony whereof I affix my signature.
GEORGE W. GREBENSTEIN.
